UNITED STATES PATENT OFFICE.

JOHN A. MEHLING, OF CLEVELAND, OHIO, ASSIGNOR TO THE MEHLING MANUFACTURING COMPANY, OF SAME PLACE.

SEAL-LOCK.

SPECIFICATION forming part of Letters Patent No. 633,875, dated September 26, 1899.

Application filed February 23, 1897. Serial No. 624,725. (No model.)

To all whom it may concern:

Be it known that I, JOHN A. MEHLING, a citizen of the United States, and a resident of Cleveland, county of Cuyahoga, State of Ohio, have invented certain new and useful Improvements in Seal-Locks, of which I hereby declare the following to be a full, clear, and exact description, such as will enable others skilled in the art to which it appertains to make and use the same.

I choose to exemplify my invention in its application to a fare-collecting box for street-railway service, a box having been selected having a sliding cover.

15 My invention consists in the fixed hook upon the cover combined with engaging mechanism upon the box, (or vice versa,) which will act to pierce a paper check or seal which is out of reach of the conductor and must be 20 acted upon before the hook can be released therefrom or the cover can be opened.

25 My invention consists in the combination and arrangement of parts and construction of details, as hereinafter described, shown in the accompanying drawings, and specifically pointed out in the claims.

30 In the accompanying drawings, Figure 1 is a front view of the upper portion of the box, partly in section, showing the cover lowered, and an edge view of the hook-engaging mechanism. Fig. 2 is a vertical transverse section of the box, showing a side view of hook-engaging mechanism and edge view of cover and hook. Fig. 3 is a top view of box. 35 Figs. 4 and 5 are views of paper check or seal. Figs. 6 and 7 are details of mechanism.

In the figures, 1 is the box-casing.

2 is the cover, which moves in grooves 3, arranged for it on either side of the casing.

40 4 is the hook. (Shown in dotted lines in Fig. 1 and in side view in Fig. 2.) This hook is securely attached to the inner face of the cover, and as the cover closes the barb of the hook comes into contact with the locking-arm or keeper 5, which is hinged upon the bell-crank 7 and is placed directly in the path of the hook.

45 The keeper 5 is hinged upon the bell-crank 7 by means of a pin 6 and is turned aside by 50 means of the hook as it passes, but is imme-

diate returned into its position, so as to lie behind the barb and prevent the opening of the cover by means of the spring 15, which is secured to the keeper and bears upon the main portion of the bell-crank 7. To release 55 the cover, the entire bell-crank is rotated in the following manner: This bell-crank is pivotally secured to the side wall of the box by means of a wrist 14, which projects through the case and is provided with a slot 17 to receive a tool or suitable means for rotating it. As seen clearly in Figs. 2 and 6, the bell-crank is provided with a projecting arm sharpened at the extremity to the cutting-point 8, which is adapted to pierce a paper 65 check or seal 9, placed where the cutting-point will engage it while the bell-crank is being rotated and before the cover can be released. The bell-crank need only be rotated far enough for the hinged keeper to pass the 70 barb of the hook, when the cover can be withdrawn. As the bell-crank is turned on its pivot, the cutting-point will cut through the paper check or seal and mark it, so as to indicate that the box has been opened.

75 The paper check is mounted loosely in guides 10, between which it is inserted before the cover is placed on the box. Over the check and over an opening 11 in the box is placed the glass 12, covered by the ring 13, thus permitting the check to be seen through the casing.

80 A spring 18, secured at one extremity to the top wall of the box and at the other extremity to the bell-crank at a distance from 85 the pivotal point, instantly returns the bell-crank to its original position, (with the keeper blocking the path of the hook and cover,) where it presses against the stop 19 upon a disk 20, which is integral with a sleeve 21, secured to the casing and through which the wrist 14 passes. This stop also receives the pull of the cover and prevents its being 90 opened until the bell-crank is turned aside from the hook.

95 It will readily be seen that it is necessary to rotate the bell-crank 7 and pierce the check before the cover can be removed, and the cover must be removed before the bell-crank is released and the spring returns it to 100

its normal position, the bell-crank being held immovable in the meantime.

Having described my invention, what I claim as new, and desire to secure by Letters 5 Patent, is—

1. The combination with the box and cover therefor of a seal-holder and seal upon one of said box portions, and means for locking the box and cover together and for defacing the seal simultaneously with the disengagement of the lock, consisting of a bell-crank adapted to be rotated from the exterior of the box, mounted upon one of said box portions, and provided with a cutter-arm, and a locking-arm or keeper adapted to engage a catch upon the other portion of the box, a stop for the bell-crank and a return-spring therefor, substantially as described.
2. The combination with the box and cover, of a seal-holder and seal, a bell-crank adapted to be rotated from the exterior of the box, and provided with a cutting-arm and a locking-arm, and mounted upon one portion of the box, and a catch upon the other portion 25 of the box, adapted to engage said locking-arm, when the cover is closed, the catch and locking-arm being adapted to pass each other

as the cover is closing, substantially as described.

3. In a seal-lock the combination with a 30 box and cover and seal-holder and seal or check, of means for locking the same and for defacing the seal or check by means of the locking mechanism while disengaging the lock, before the cover can be released, consisting of a bell-crank operated from outside the box, and provided with defacing and locking arms, and mounted upon one portion of the box, in combination with a catch on the other portion of the box, substantially as described.

4. In a seal-lock the combination with the box and cover therefor, of a seal-holder and seal, a locking-arm and catch, one upon the cover and the other upon the box, and an oscillating cutter-arm secured to the catch and adapted to deface the seal when the locking-arm and catch are disengaged, before the cover can be released, substantially as described.

JOHN A. MEHLING.
